UNITED STATES PATENT OFFICE.

GUY R. LANMAN, OF EL RENO, OKLAHOMA.

SPARK-PLUG PROTECTOR.

1,245,931.

Specification of Letters Patent.

Patented Nov. 6, 1917.

Application filed November 4, 1916. Serial No. 129,558.

To all whom it may concern:

Be it known that I, GUY R. LANMAN, a citizen of the United States, residing at El Reno, in the county of Canadian and 5 State of Oklahoma, have invented new and useful Improvements in Spark-Plug Protectors, of which the following is a specification.

This invention relates to spark plug protectors, the object in view being to provide a spark plug protecting device which may be readily applied to any spark plug whether applied to or detached from a cylinder and which when in its proper position will protect the spark plug from being struck by flying or falling objects, which will also prevent water from reaching the spark plug and causing a short circuit and which will also protect and hold a sufficient portion of 20 the circuit wire leading to the plug to prevent said wire from sagging and causing the extremity thereof to become loose or detached from the binding post thereof.

With the above and other objects in view 25 the invention consists in the novel construction, combination and arrangement of parts, herein described, illustrated and claimed.

In the accompanying drawing:—

Figure 1 is a side elevation of the device 30 shown applied to a spark plug in turn shown applied to a fragment of a cylinder.

Fig. 2 is a vertical longitudinal section through the protector, showing the plug and a portion of the circuit wire in elevation.

Fig. 3 is a perspective view of the protector detached.

The protector contemplated in this invention, in the preferred embodiment thereof is formed of sheet metal in a single piece, the 40 metal being of any suitable thickness or gage. The metal blank is so shaped and cut that when folded or rolled into its final shape, the protector comprises a vertical arm or leg 1, and a substantially horizontal arm or leg 2 which is smaller in cross section 45 than the arm or leg 1 and preferably made tapering from its point of junction from the arm 1 to the extremity of the arm 2, both arms being tubular in cross section but being 50 split longitudinally as indicated at 3 and 4.

The long and short arms or legs of the device are connected together in the form of an elbow 5 and the internal dimensions of said elbow and also of the arm or leg 1 are 55 such as to prevent the binding post or upper extremity of the power electrode and the

current wire from coming in contact with the protector which would cause a short circuit.

The vertical arm of the protector is provided adjacent to the lower extremity thereof with substantially parallel projecting ears or lugs 6, one of which has its marginal portions turned outwardly to provide flanges 7 extending at right angles to each other to 60 embrace a nut 8 which is held by the flanges and prevented from turning. If desired the nut 8 may be soldered or otherwise permanently fastened to said flanges. A clamping screw 9 is inserted through both of the ears 65 or lugs and through said nut so that by tightening said screw, the lower marginal portion of the vertical leg of the device is clamped securely around the plug and in this way the device as a whole is positioned 70 upon the plug and securely held in fixed relation thereto.

In like manner the extremity of the horizontal or overhanging arm or leg of the protector is formed with substantially parallel 80 ears or lugs 10 one of which is marginally bent to provide flanges 11 to embrace a nut 12 and prevent the latter from turning. This nut like the one at the face of the upright portion of the protector may be soldered or 85 otherwise permanently fastened in place. A clamping screw 13 is inserted through the ears or lugs at the extremity of the overhanging arm for the purpose of contracting the extremity of said arm around an insulating washer or bushing 14 inserted in the end 90 of said overhanging arm and having an opening through which the current wire 15 passes, said wire being connected by a terminal 16 to the binding post or electrode of 95 the plug in the usual way.

From the foregoing description taken in connection with the accompanying drawings, it will now be apparent that the plug and the adjacent portion of the wire leading to the plug, as well as connections between the wire and plug are all protected against the entrance of water and against being struck by flying or falling objects. The plug and its connections are kept free 100 from dirt, the wire leading to the plug is prevented from vibrating close to the plug thereby preserving the connections between the wire and the plug and preventing the breakage of the wire at such point through 110 crystallization of from other causes. The bushing at the extremity of the overhanging

arm of the device prevents water, lubricating oil and the like from finding its way along the wire to the plug.

While I have described the protector as constructed of metal, it will of course be understood that any suitable material may be employed in the construction of said protector such as rubber, asbestos and the like. I do not desire to be limited to the particular 10 form of protector herein shown and described as it will be apparent that the device is susceptible to changes in the form proportion and minor details of construction which may accordingly be resorted to without departing from the principle or sacrificing any of the advantages of the invention.

The protector herein above described is preferably so constructed that it will spread to enable it to be associated with the conductor or wire and plug without disconnecting the wire from the plug, the metal of which the protector is formed having sufficient spring or resiliency to allow for its operation. If desired the protector may be 20 lined throughout with insulating material to prevent any possibility of short circuit.

I claim:—

1. The combination with a spark plug, a feed wire leading thereto, of a protector constructed to cover the upper portion of the 30 plug and the adjacent portion of the feed wire, said protector embodying two tubular arms extending at an angle to each other and split longitudinally, and means on one of said arms for clamping the same around a spark plug.

2. The combination with a spark plug, a feed wire leading thereto, of a protector constructed to cover the upper portion of the plug and the adjacent portion of the feed 40 wire, said protector embodying two tubular arms extending at an angle to each other and split longitudinally, means on one of said arms for clamping the same around a spark plug, an insulating bushing in the 45 other arm of the protector through which the lead wire passes, and means carried by the last named arm for clamping said bushing in place.

In testimony whereof I affix my signature. 50

GUY R. LANMAN.
